UNITED STATES PATENT OFFICE.

FREDERIC BARNES WALDRON, OF PRESCOT, ENGLAND, ASSIGNOR TO PILKINGTON BROTHERS LIMITED, OF ST. HELENS, ENGLAND, A LIMITED LIABILITY COMPANY OF ENGLAND.

APPARATUS FOR HOLDING AND LIFTING BY MEANS OF SUCKERS.

1,426,692.

Specification of Letters Patent. Patented Aug. 22, 1922.

Application filed October 6, 1920. Serial No. 415,121.

To all whom it may concern:

Be it known that I, FREDERIC BARNES WALDRON, a subject of the King of the United Kingdom of Great Britain and Ireland, and residing at Eccleston Park, Prescot, in the county of Lancaster, England, have invented new and useful Improvements in Apparatus for Holding and Lifting by Means of Suckers, of which the following is a specification.

This invention relates to apparatus for holding and lifting by means of suckers, and as it is particularly applicable for holding and lifting plates of glass, the following description deals with it only in that connection. The invention has for its object to provide new or improved apparatus whereby large plates of glass may be lifted from a horizontal position by a crane, transported thereby in a vertical or nearly vertical position and placed either on edge on racks or in a horizontal position.

This improved apparatus is more especially designed for lifting plates of glass in the course of their manufacture, in which they are bedded on to the grinding and polishing tables and have to be lifted therefrom. The plates when so bedded, adhere so firmly to the tables that it is impracticable, unless by the use of very powerful apparatus, to lift them by a direct vertical pull, and, when being lifted by hand, they have to be raised first at one edge and, as it were, peeled off the table, the flexibility of the plates permitting this peeling action.

The lifting apparatus which forms the subject of this invention, imitates this action of lifting by hand, and, under the hoisting action of the crane, lifts the plate first at one edge and, by allowing it to bend, peels it off the table.

In the accompanying drawing,

Figure 1, is a front elevation showing the apparatus as when suspended from the crane and holding in a vertical plane, a plate of glass not represented in the figure.

Figure 2 is a sectional view taken along the line A—A of Figure 1, showing on an enlarged scale, a portion of the apparatus when in a horizontal position, and

Figure 3 is a view of a portion of Fig-

ure 2 on an enlarged scale, showing a modified form of the apparatus.

In the construction represented in the drawing, which is to be taken merely as a convenient example, the frame of the apparatus is composed of a channel bar 1, to which are bolted cross arms 2, 2, by bolts 15, 15. At each end of each cross arm 2, is supported a sucker 3, and these suckers are connected to pipe junctions 4, 4, by rubber or other flexible connecting pipes 5, 5, while the pipe junctions 4, 4, are connected together and to a T-piece 7, by pipes 6. A flexible pipe 8, connected to the T-piece 7, connects the suckers 3, through the system of pipes to an air-exhausting means. The apparatus is supported from the crane by a sling 10, 10, pivoted in lugs 9, 9, fixed to the channel bar 1.

The crane sling 10, 10, is attached symmetrically to the centre of the apparatus in the direction of the length of the channel bar 1, but, in the other direction, it is attached on a line nearer to one side (that is to say, to the top as seen in Figure 1) of the apparatus. Further, as shown in Figure 2, the common axis of the sling pivots, is as close as practicable to the plane of the faces of the suckers, so that when the apparatus is lifted, as in Figure 1, carrying a plate of glass, it hangs nearly vertically, and is therefore in a convenient position for transport and for placing said plate on edge on racks.

When the apparatus is placed centrally on the plate of glass and is attached thereto by the suckers 3, the pull of the crane acts most on that edge of the plate to which the lugs 9, 9, are nearest, and lifts this edge first, and then gradually brings the plate more and more towards the vertical until said plate leaves the table.

In order to secure the peeling off action above mentioned, the glass plate must be allowed to bend when being lifted and to permit this bending, the suckers 3 are supported loosely on the cross arms 2.

As shown in Figure 2, a bolt 11 is rigidly attached to the body 12 of the sucker 3, and passes through a hole in the end of the cross arm 2, the hole being larger than the bolt so as to allow play between them. There

is also play between the upper surface of the end of the cross arm 2 and a shoulder 13 of the bolt 11. The sucker, therefore, can, within small limits, take up any angular position with reference to the frame, and all suckers can consequently remain in contact with the plate when this is bent.

In order that the apparatus may be employed to lift both small and large plates, 10 valves 14, 14, are provided in the pipes 6, 6, leading to the two outer pairs of suckers 3, so that when one or both of these pairs are beyond the edges of the plate, the respective valve 14 or both of them may be 15 closed and the corresponding suckers put out of action.

In the case of larger plates, the whole apparatus may be attached nearer to one side of the plate than to the other, so that the 20 initial pull of the crane may act as close as possible to one edge of the plate. This same action is secured even in the case of plates which are so small that the apparatus has to be attached to them centrally, by reason 25 of the lugs 9, 9, being nearer to one side of the apparatus than to the other.

To enable the suckers 3 securely to hold rough cast glass or glass that is warped, it is preferred to make the frame of the apparatus flexible so that any one of the cross 30 arms 2, 2 can, within small limits, take up any angular position relatively to the plane of the frame. For this purpose the frame would preferably be made flexible by so attaching the cross arms 2, 2 to the channel bar 1, as to permit of limited relative motion between these parts. Any convenient mechanical construction may be adopted to secure this freedom of the cross arms, for example, in the construction of frame shown, 35 in Figure 3 it is conveniently obtained by leaving the bolts 15, 15 slightly slack.

The invention is not confined to the particular design and construction of apparatus shown and described, but it is an essential feature of the invention that the suckers should be so attached to the frame of the apparatus, that they can remain in contact with the plate of glass when this latter bends under the action of pulling it off the table.

Having described my invention, I declare that what I claim and desire to secure by Letters Patent is:—

1. In apparatus for lifting and carrying 55 glass plates, the combination of a frame, suckers thereon adapted to be attached to

glass plates by suction and a carrying sling pivoted to the frame on an axis nearer to one side of the frame than to the other.

2. In apparatus for lifting and carrying 60 glass plates, the combination of a frame, suckers thereon adapted to be attached to glass plates by suction, a carrying sling pivoted to the frame on an axis nearer to one side of the frame than to the other and as close as is constructionally practicable to the plane containing the faces of the suckers.

3. In apparatus for lifting and carrying 70 glass plates, the combination of a longitudinal member and cross members attached to the longitudinal member to form a frame, suckers thereon adapted to be attached to glass plates by suction, and a carrying sling pivoted to the frame on an axis nearer to one side of the frame than to the other. 75

4. In apparatus for lifting and carrying 80 glass plates, the combination of a longitudinal member and cross members attached to the longitudinal member to form a frame, suckers thereon adapted to be attached to glass plates by suction, a carrying sling pivoted to the frame on an axis nearer to one side of the frame than to the other and as close as is constructionally practicable to the plane containing the faces of the suckers. 85

5. In apparatus for lifting and carrying 90 glass plates, the combination of a longitudinal member and cross members, means for attaching the cross members to the longitudinal member to form a frame and permit a small movement of the cross members out of their general plane, suckers on the cross members adapted to be attached to glass plates by suction and a carrying sling pivoted to the frame on an axis nearer to one 95 side of the frame than to the other.

6. In apparatus for lifting and carrying 100 glass plates, the combination of a longitudinal member and cross members, means for attaching the cross members to the longitudinal member to form a frame and permit a small movement of the cross members out of their general plane, suckers on the cross members adapted to be attached to glass plates by suction, a carrying sling pivoted 105 to the frame on an axis nearer to one side of the frame than to the other and as close as is constructionally practicable to the plane containing the faces of the suckers.

In testimony whereof I have affixed my 110 signature hereto.

FREDERIC BARNEs WALDRON.
